UNITED STATES PATENT OFFICE.

MARTHA HALOWELL CONNER, OF BALTIMORE, MARYLAND, ASSIGNOR TO TIN DECORATING COMPANY OF BALTIMORE, OF BALTIMORE, MARYLAND.

DESIGN FOR A SIFTER-TOP OR SIMILAR RECEPTACLE.

52,305.

Specification for Design.

Patented Aug. 27, 1918.

Application filed February 9, 1918. Serial No. 216,381. Term of patent 7 years.

To all whom it may concern:

Be it known that I, MARTHA HALOWELL CONNER, a citizen of the United States, residing in the city of Baltimore, State of Maryland, have invented a new, original and ornamental Design for Sifter-Tops or Similar Receptacles and Particularly Those of the Sifter-Head Type, of which the following is a specification, reference being had to the accompanying drawing, forming a part thereof, wherein—

Figure 1 is a top plan view of a vessel or receptacle of the sifter head type showing my improved ornamental design applied thereto.

Fig. 2 is a front elevation showing my improved ornamental design applied to a receptacle of the sifter head type.

What I claim is—

The ornamental design for a sifter top or similar receptacle as shown.

MARTHA HALOWELL CONNER.
